United States Patent Office

Des. 193,746
Patented Oct. 2, 1962

193,746

HANGER OR SIMILAR ARTICLE

Oscar Cohen, New York, N.Y.
(125—10 Queens Blvd, Kew Gardens, Queens, N.Y.)

Filed Apr. 26, 1962, Ser. No. 69,860

Term of patent 3½ years

(Cl. D80—8)

FIG. 1 is a front elevation view of a hanger or similar article showing my new design.

FIG. 2 is a top plan view thereof.

I claim:

The ornamental design for a hanger or similar article, as shown.
